Primary Examiner — Melanie Pellegrini(57) **CLAIM**

The ornamental design for a watch band, as shown and described.

DESCRIPTION

FIG. 1 is a perspective isometric view of a watch band showing my new design.

FIG. 2 is a front side elevation view of FIG. 1.

FIG. 3 is a rear side elevation view of FIG. 1.

FIG. 4 is a left side elevation view of FIG. 1.

FIG. 5 is a right side elevation view of FIG. 1.

FIG. 6 is a top side plan is a view of FIG. 1; and,

FIG. 7 is a bottom side plan view of FIG. 1.

The features shown in dash-dot lines in the drawing depict portions of the watch bands. The dash dot dash lines define the bounds of the claimed design. The broken lines form no part of the claimed design and any shading is not a feature of the design but is utilized to illustrate the surface contours of the watch band in the drawings.
